UNITED STATES PATENT OFFICE

2,379,772

ELECTROMAGNETIC RELAY

Albert Wellman, Scotia, N. Y., assignor to General Electric Company, a corporation of New York

Application September 2, 1943, Serial No. 500,992

4 Claims. (Cl. 200—111)

My invention relates to electromagnetic relays, particularly to totally enclosed solenoid type relays, and has for its object the provision of a new and improved relay of this type characterized particularly by reliability in operation and simplicity of assembly and disassembly. Such a relay is low in cost and adapted for quick, easy and inexpensive manufacture in large quantities.

According to my invention, all the parts of both the magnetic and electrical circuits are held in operative relation solely by the closure members of an outer insulating casing.

The novel features which are characteristic of my invention will be set forth with particularity in the claims appended hereto. The invention will be better understood, however, and its objects and advantages more fully appreciated by referring first to the following detailed specification taken in conjunction with the accompanying drawing in which Fig. 1 is a plan view of one end of a relay embodying my invention; Fig. 2 is a cross-sectional view taken along the line 2—2 of Fig. 1; Fig. 3 is a plan view of the opposite end of the relay with the enclosing cover removed; and Fig. 4 is an exploded perspective view of the entire relay.

Referring now to the drawing, I have shown an electromagnetic relay comprising a cylindrical enclosing casing 10, preferably formed of a suitable non-magnetic electrically insulating material, and having an external peripheral shoulder 11 slightly spaced from one end thereof. Between the peripheral shoulder 11 and the adjacent end of the casing 10, the casing 10 is of somewhat reduced external and internal diameter thereby to provide an internal peripheral shoulder 11a in substantially the same plane as the shoulder 11. The reduced section of the casing 10 is provided with two pairs of diametrically disposed longitudinal slots 12 and 13. As shown at Fig. 2, the internal shoulder 11a is cut away above the slots 12 and 13 to provide internal longitudinal recesses 11b for a purpose which will appear more fully hereinafter. The peripheral shoulder 11 is cut away at diametrically opposite points 15.

The opposite end of the casing is provided with one pair of diametrically disposed longitudinal slots 14. The slots 14 extend farther longitudinally on the outer surface of the casing than on the inner surface, thereby to provide a pair of shoulders 16 at the bases of these slots. Opposite ends of the cylindrical casing 10 are threaded to receive a pair of end caps 17 and 18, preferably formed of the same non-magnetic electrically insulating material as the casing 10. The end caps 17 and 18 are generally cup-shaped and the cap

18 is provided internally with a hollow cylindrical boss 19 for a purpose which will be more fully described hereinafter.

Removably disposed within the casing 10 is a metallic liner 20 of magnetizable material having at one end a pair of diametrically disposed longitudinal slots 21. A pair of diametrically opposite bosses 20a on the liner 20 are arranged for cooperation with a pair of diametrically opposite grooves 10a on the inner surface of the casing 10 to align the slots 21 with the slots 14 when the parts are in assembled position. Within the liner 20, is removably positioned a cylindrical energizing coil 22 having attached to one end thereof, at diametrically opposite points, a pair of off-set terminal connectors 23. In the assembled position shown at Fig. 2, the terminal connectors are so arranged that their off-set portions overlie the shoulders 16 at the bases of the slots 14 in the casing 10. In this position, the terminal connectors 23 do not interfere with the threaded engagement of the end cap 17 within the casing 10, but their radially extending outer ends are firmly clamped between the end cap 17 and the shoulders 16.

Between the upper end of the energizing coil 22, as viewed in the drawing, and the upper end cap 17 is disposed a metallic disk 24 of magnetizable material having at the center thereof a hollow cylindrical boss 26 arranged to extend a short distance longitudinally into the coil 22. The hollow boss 26 is lined with a cup-shaped liner 27, preferably formed of a non-magnetizable metal characterized by long wearing qualities. The cup-shaped liner 27 provides a permanent "air gap" and also serves slidably to support a magnetizable plunger 28 which extends into the coil 22 and is provided with a conical face 29. To prevent the formation of an air cushion between the plunger 28 and liner 27, the base of the liner 27 is apertured at 21a and the end cap 17 is formed with a circular internal boss 17a thereby to provide a small air space 17b between the disk 24 and the end cap 17. Since the liner 27 constitutes a necessary and permanent "air gap" or break in the magnetic circuit, its reluctance is minimized by forming the liner to present a large area for the passage of magnetic flux between the plunger 28 and the end cap 24.

It will be noted that the portion of the plunger 28 which slides within the liner 27 is of smaller diameter than the plunger head. This reduction of the plunger diameter makes possible the large flux area through the liner 27. It should be noted that leakage flux between the lower end of the cylindrical boss 26 and the plunger head provides a hold-out force which must be minimized.

Such force is satisfactorily reduced by making the minimum length of this leakage flux path at least two or three times the length of the air gap through the liner 27.

Extending into the coil 22 from the opposite end thereof I provide a magnetizable core member 30 having a reentrant conical face 31 for cooperation with the conical face 29 of the plunger 28. The core 30 is mounted at its other end upon a magnetizable disk 32 which extends across the lower end of the coil 22 between the stationary core portion 30 and the magnetizable liner 20, thereby to complete a magnetizable frame for the relay.

The stationary core 30 and the magnetizable end disk 32 are centrally bored along the longitudinal axis of the core 30 slidably to receive an actuating pin 33 which is preferably formed of non-magnetizable material. The pin 33 extends beyond both ends of the magnetizable core 30, the upper end of the pin having a reduced end portion 34 fitting into a bore in the end of the movable plunger 28. The lower end of the pin 33 has a reduced end portion 35 which fits snugly into a knob 36 having a peripheral shoulder 37 at the upper end thereof. Beneath the magnetic disk 32, and seated upon the internal shoulder 11a of the casing 10, I provide an insulating disk or washer 38. The washer 38 effectively divides the casing 10 into an upper coil compartment and a lower contact compartment. The parts thus far described in the coil compartment are all clamped in operative relation between the shoulder 11a and the upper end cap 11. The actuating pin 33 passes slidably through the washer 38 so that the knob 36 lies in the lower or contact compartment.

Referring now to the lower end of the relay, as viewed in the drawing, there are radially disposed within the pairs of diametrical slots 12 and 13 two pairs of contact strips 39 and 40. Each contact strip 39 is flat and is provided internally and externally with keying portions to prevent radial displacement of the strip with respect to the casing 10. The strips 39 are enlarged both internally and externally to key the strips against radial displacement, the internal enlargements serving as fixed contact surfaces and the external enlargements serving as terminal connectors. The contact strips 40 are offset so that their inner and outer portions lie in different planes. The outer portions only of the contact strips 40 are enlarged to provide terminal connections and keying connection with the slots 12. These outer portions of the strips 40 lie against the lower surface of the external peripheral shoulder 11 on the casing and in the same plane as the outer portions of the contact strips 39. Within the slots 12, however, the contact strips 40 are off-set and extend a small distance longitudinally of the casing 10. The off-set in the contact strips 40 serves both to dispose the inner ends of the contact strips 40 in a plane displaced from the plane of the inner ends of the contact strips 39, and also as a key to prevent outward radial displacement of the contact strips 40 with respect to the casing 10. Because of the off-set in the contact strips 40, it is unnecessary to provide enlarged inner keying portions for these strips. The contact strips 40, like the contact strips 39, serve the dual purpose of providing at their inner ends fixed contact surfaces and at their outer ends terminal connectors. Both pairs of contact strips 39 and 40 are clamped firmly in place, in the assembled

position of the relay, between the end cap 18 and the lower surface of the external peripheral shoulder 11 on the casing 10.

Referring now particularly to Figs. 2 and 3, it may be observed that I provide between the planes of the contact strips 39 and the inner ends of the contact strips 40 an S-shaped movable contact element 41. The contact element 41 is preferably formed of electrically conducting spring material and comprises a diametrical member having a hole at the center thereof and arcuate portions extending oppositely from the ends thereof. It will be observed from Figs. 2 and 3 that the movable contact member 41 is mounted upon the collar 36 in such a position that the diametrical body portion of the contact member serves as a bridging contact between the fixed contact strips 39 and the arcuate extensions of the member 41 are disposed to engage the fixed contact strips 40. To opposite ends of the movable contact member 41 are attached a pair of moving contacts 41a and 41b, which, in operative position, extend a small distance into the internal recesses 11b to limit rotation of the contact member 41 with respect to the casing 10 thereby to maintain the moving contacts in proper alignment with the fixed contacts.

The movable contact member 41 is biased upwardly and into engagement with the shoulder 37 on the knob 36 by means of a helical compression spring 42 which is seated at one end in the hollow cylindrical boss 19 of the end cap 18 and the other end of which holds the contact member 41 against the shoulder 37. The spring 42 biases the moving contact member 41 and actuating pin 33 upwardly, as viewed in the drawing, so that the member 41 normally engages the fixed contact strips 40. In this position the movable plunger 28 is also held spaced from the magnetizable core 30.

In operation, the movable bridging contact 41 normally completes a circuit between the fixed contact members 40. The contact 41 is movable between the fixed contacts 40 and the fixed contacts 39, the fixed contacts 39 being shown in the drawing below the movable contact member. Thus, when the actuating coil 22 is energized, the movable plunger 28 is drawn downwardly into engagement with the magnetizable core 30 and presses the actuating pin 33 downwardly against the bias of the compression spring 42. In its downward movement, the actuating pin 33 carries with it the knob 36 and the movable contact member 41 mounted thereon, thereby to move the contact member 41 out of engagement with the fixed contacts 40 and into engagement with the normally open fixed contacts 39.

To facilitate mounting of my relay upon any suitable base, which may be a vertical or horizontal surface, I provide a mounting bracket 43 encircling the casing 10 and having a pair of attachment feet extending through the cutaway portions 15 of the shoulder 11. The bracket 43 is formed of spring material and is slightly bent diametrically at 43a to provide some resilience in the mounting.

In view of the foregoing detailed explanation of the structure and arrangement of the various parts of my relay, it will now be evident that all parts of my relay are readily accessible and that the whole is simply and easily assembled or disassembled. In assembly, the mounting bracket 43 is first slipped over the relay casing 10 and

its legs passed through the cutaway sections 15 of the shoulder 11. The insulating disk 38 is then slipped into the casing from the upper end and placed against the internal peripheral shoulder 11a in the casing. The connected disk 32 and core 31 are then slipped into the casing on top of the insulating disk 38. Next, the liner 20 may be placed in the casing and the slots 21 aligned with the slots 14. The coil 22 is then slipped into the lining and the terminal connectors 23 disposed in their proper position in the slots 14. Next, the movable plunger 28 is placed in the magnetizable disk 24 and both elements together placed on top of the coil 22. The upper end assembly may now be completed by screwing the end cap 17 in place. Turning the relay upside down, the actuating pin 33, with the knob 36 attached, may be placed in the core and the movable contact member 41 slipped over the end of the knob 36 and against the shoulder 37. The pairs of stationary contacts 39 and 40 are now slipped longitudinally into their respective pairs of slots 13 and 12, the inner ends of the contacts 40 being placed under the contact member 41 and the inner ends of the contacts 39 being placed over the member 41. Finally, the helical compression spring 42 is placed in the boss 19, where it is frictionally held sufficiently to permit it to be inverted over the end of the knob 36, and the end cap 18 is screwed in place to clamp the fixed contacts 39 and 40 in their operative positions. The relay is now totally enclosed, substantially dustproof and waterproof, and may if desired be hermetically sealed. Finally, the relay may be mounted upon any suitable base by means of the mounting bracket 43.

While I have described only one preferred embodiment of my invention by way of illustration, many modifications will occur to those skilled in the art and I therefore wish to have it understood that I intend in the appended claims to cover all such modifications as fall within the true spirit and scope of my invention.

What I claim as new and desire to secure by Letters Patent of the United States is:

1. An electromagnetic relay comprising an open-ended cylindrical casing of non-magnetic insulating material provided with internal and external peripheral shoulders adjacent one end, said casing being slotted longitudinally at diametrically opposite points between said one end and said shoulders, an insulating washer seated on said internal shoulder to divide said casing into coil and contact compartments, a removable cylindrical liner of magnetizable material disposed within said coil compartment, a removable cylindrical energizing coil disposed within said liner, a magnetizable core centrally positioned in said coil and extending from said washer partially through said coil, a magnetizable plunger within said coil movable longitudinally into and out of engagement with said core, a pair of magnetizable disks disposed at opposite ends of said coil to complete a magnetic frame for said relay, one of said disks being attached to one end of said core and the other of said disks slidably receiving one end of said plunger, a pair of fixed contacts extending radially through the longitudinal slots of said casing into said contact compartment, a slidable actuating rod extending from said plunger through said core and into said contact compartment, a movable contact member mounted upon the extending end of said rod, a pair of end caps of non-

magnetic insulating material attached to opposite ends of said casing to close said compartments and to hold the parts of said relay in fixed operative relation, and a compression spring interposed between the contact compartment closure cap and said movable contact member, said contact compartment closure cap clamping said fixed contacts in fixed position against said external casing shoulder.

10 2. An electromagnetic relay comprising an open-ended cylindrical casing of non-magnetic insulating material having a peripheral shoulder axially spaced from one end thereof, said casing being slotted longitudinally between said peripheral shoulder and said one end, an energizing coil disposed within said casing, a plunger movable axially of said casing within said coil, a movable contact member operatively connected to said plunger, a contact strip extending radially through said slot and having keying portions internally and externally of said casing, and an end cap of non-magnetic insulating material threadedly engaging said one end of said casing to close said casing and to clamp said contact strip between said cap and said shoulder, whereby the inner end of said strip provides a fixed contact surface and the outer end of said strip provides a terminal connector.

3. An electromagnetic relay comprising an open-ended cylindrical casing of non-magnetic insulating material having a peripheral shoulder axially spaced from one end thereof, said casing being slotted longitudinally at diametrically opposite points between said peripheral shoulder and said one end, an energizing coil disposed within said casing, a plunger movable axially of said casing within said coil, a movable bridging contact operatively connected to said plunger, a contact strip extending radially through each of said slots and having keying portions internally and externally of said casing, and an end cap of non-magnetic insulating material threadedly engaging said one end of said casing to close said casing and to clamp said contact strips between said cap and said shoulder, whereby the inner ends of said strips provide fixed contact surfaces and the outer ends of said strips provide terminal connectors.

4. An electromagnetic relay comprising an open-ended cylindrical casing of non-magnetic insulating material having internal and external peripheral shoulders axially spaced from one end thereof, said casing being slotted longitudinally at diametrically opposite points between said shoulders and said one end, an insulating washer seated upon said internal shoulder to divide said casing into separate coil and contact compartments, an energizing coil disposed within said coil compartment, a plunger movable axially of said casing within said coil, a movable bridging contact positioned in said contact compartment and operatively connected to said plunger, a pair of contact strips extending radially through said slots and having keying portions internally and externally of said casing, an end cap of non-magnetic insulating material threadedly engaging said one end of said casing to close said contact compartment and to clamp said contact strips between said cap and said external shoulder, and a compression spring seated against said cap and engaging said bridging contact to bias said bridging contact to a normal position with respect to said fixed contacts.
